BOBBY SOCK

Clifton T. Collins, Winston-Salem, N. C., assignor
to Rosebud Morse Garriott

Application September 8, 1952, Serial No. 21,381

Term of patent 14 years

(Cl. D47—7)

To all whom it may concern:

Be it known that I, Clifton T. Collins, a citizen of the United States, residing at Winston-Salem, in the county of Forsythe and State of North Carolina, have invented a new, original Design for a Bobby Sock, of which the following is a specification, reference being made to the accompanying drawing, forming part thereof, and in which:

Fig. 1 is a side elevation view of the sock of my new design; and

Fig. 2 is a greatly enlarged portion of the cuff defined by the dotted lines in Fig. 1.

I claim:

The ornamental design for a bobby sock, substantially as shown.

CLIFTON T. COLLINS.
